CABLE LASHING MACHINE

Dory J. Neale, Topeka, Kans.

Application November 14, 1945, Serial No. 628,450

12 Claims. (Cl. 175—376)

1

This invention relates to cable lashing machines such as used for spinning a lashing wire about an aerial cable and its supporting strand or messenger.

Machines of this character usually include a trolley adapted to be moved along the messenger and which carries a spinning head for effecting revolution of a coil of lashing wire to lay the wire in spiral formation about the cable and messenger incidental to movement of the trolley. The spinning head is somewhat spool-shaped so that the messenger and cable extend substantially axially therethrough and the head rotates therearound to lay the lashing wire. Consequently, annular tracks or supports are provided for the spinning head on the trolley. Provision must also be made to drive the spinning head responsive to movement of the trolley along the messenger. These requirements have heretofore necessitated relatively complex driving structures involving the use of gates to permit removal of the lashing machine at the completion of a span at one side of a pole and re-application of the machine to the next span at the opposite side of the pole. Another difficulty is that the driving wheel may slip on the cable supporting strand by reason of wet or greasy spots thereon so that proper tension is not maintained on the lashing wire or strand.

Therefore, principal objects of the present invention are to provide a cable lashing machine of simple, light weight construction and which is readily removed and applied to a cable supporting strand in an expeditious manner, and to provide a dual drive, one through traction on the cable supporting strand and the other responsive to withdrawal of the lashing strand from the spinning head so that at least one of the drives is always effective.

Other objects of the invention are to provide a cable lashing machine with driving connections that simplify removal and application of the machine to a cable and supporting messenger; to provide the trolley and spinning head with registerable passageways or gaps through which the cable and supporting strand pass when removing and mounting the machine; to provide a locking mechanism for retaining the trolley and spinning head with the passageways or gaps in registry; to provide an improved driving mechanism that eliminates the necessity of connection and disconnection with respect to the driving head; to provide a rolling support for the driving head which acts in conjunction with the driving connection to maintain fixed alignment

2

ment and driving engagement of the driving head in all positions thereof; to provide the trolley with a traction wheel driven by traction with the messenger to operate the driving connection with the spinning head; to provide readily adjustable means for maintaining desired tractive contact of the wheel with the messenger; to provide the lashing machine with means for collecting and supporting the rings by which the cable is temporarily carried from the messenger; and to provide an improved tensioning mechanism for applying the desired amount of tension on the lashing wire as it is being laid around the cable and its supporting messenger.

In accomplishing these and other objects of the invention I have provided improved structure, the preferred form of which is illustrated in the accompanying drawings wherein:

Fig. 1 is a perspective view of a cable lashing machine constructed in accordance with the present invention and showing the machine in use for lashing a cable to a supporting strand.

Fig. 2 is a cross section through the machine, particularly illustrating the driving connection with the spinning head.

Fig. 3 is a detail section particularly illustrating mounting of the cable guiding roller.

Fig. 4 is a longitudinal section through the machine and showing the machine applied to the messenger which supports the cable.

Fig. 5 is a plan view of the machine, partly in section and partly broken away to better illustrate the construction.

Fig. 6 is a fragmentary sectional view particularly illustrating the locking device between the spinning head and trolley.

Fig. 7 is a perspective view of the cable lashing machine particularly illustrating the machine prepared for application to a messenger.

Fig. 8 is a detail section through the latch for locking the single gate used in the machine.

Fig. 9 is a section illustrating the ratchet mechanism for preventing retractive movement of the trolley on the messenger and for maintaining tension on the lashing wire whenever forward movement of the trolley is suspended.

Fig. 10 is a perspective view of the tensioning levers for maintaining desired tractive contact of the foremost trolley wheel with the messenger.

Referring more in detail to the drawings: 1 designates a cable lashing machine embodying the features of the present invention and which includes a trolley 2 and a spinning head 3. The trolley 2 includes a substantially tubular

body 4 having a longitudinal slot or gap 5 in the underside thereof to permit mounting of the machine on a cable supporting strand as later described. The ends of the tubular body are provided with flanges 6 and 7 (Fig. 4) to which are bolted substantially disk-like heads 8 and 9. The heads 8 and 9 have slot-like openings or gaps 10 and 11 (Figs. 4 and 7) registering with the longitudinal gap 5 of the tubular body 4. The head 9 has a track 12 extending therearound to cooperate with a track member 13 (Figs. 4 and 5) that is interposed between the flanged end 6 of the tubular body 4 and the head 8. The surfaces 14 of the track are preferably formed on an angle of substantially 45° relative to the axis of the tubular body. The heads, including the track member 13, are bolted to the tubular body by suitable fastening devices such as bolts 15 and 16 respectively (Fig. 4). Mounted on the rear face of the head 9 is a wheel housing 17 including an upper fixed section 18 and a lower hinge section 19. The upper section 18 has a radial flange 20 extending outwardly therefrom to secure the section to the head 9 by means of fastening devices 21 that pass through suitable openings in the flange and into threaded sockets of the head. The lower section conforms in shape to the upper section and has an ear 22 (Fig. 5) projecting from the flange 23 (Fig. 7) thereof which forms a continuation of the flange 20. The hinge section is secured to the head 9 by a fastening device such as a cap screw 24 (Fig. 5) that extends through an opening in the ear and into a threaded opening of the flange of the head. The opposite end of the flange 23 engages in a keeper 25 (Fig. 5) that is offset laterally from the adjacent face of the head 9 to support the sections in registry. The annular wall of the sections curves inwardly as at 26 to encircle a circular opening 27 that registers with the passageway 28 through the tubular body (Fig. 4). The hinge section carries a block 29 (Figs. 4 and 7) that is fixed to an inwardly extending lug 30 of the section and which engages in and closes the notch-like opening or gap 11 of the head 9 and provides a continuation of the track 12. The hinge section 19 is adapted to be latched in closed position relative to the fixed section of the housing by a slide bolt 31 reciprocable in a bore 32 of the block 29 and engageable in a registering bore 33 formed in the head 9, the bolt being normally projected by a spring 34 (Fig. 8) seated in the bottom of the bore 32 and engaging the end of the bolt 31. The bolt is moved to retracted position against action of the spring 34 by means of a lateral pin 35 which projects through a slot 36 in the block 29 as shown in Fig. 4.

Extending inwardly from the upper section of the housing are spaced lugs 37 and 38 mounting the ends of a cross pin 39 which journals a wheel 40. The wheel 40 has a grooved periphery 41 conforming to the contour of a cable supporting strand or messenger and on which the wheel is adapted to roll for supporting that end of the trolley. Co-operating with the wheel 40 is a roller 42 that is journaled on a cross pin 43 carried by spaced arms 44 and 45, which arms are pivoted on a cross pin 46 (Fig. 4) carried by the lug 30 previously described. The arms 44 and 45 are adapted to be moved toward the wheel 40 to engage the underside of a cable supported by the messenger. This movement is effected by means of set screws 47 threaded angularly

through openings passing through the hinged section 19 of the housing and through internal lugs 48 to engage the undersides of the arms 44 and 45 as shown in Figs. 4 and 7. The rear end of the trolley is guided laterally with respect to the messenger by laterally spaced vertically disposed rollers 49 and 50 that are carried on arms 51 and 52 pivotally mounted within the upper housing section on cap screws 53 (Fig. 5) which are secured to the lugs 37 and 38. The arms are retained against adjusting screws 54 and 55 by coil springs 56 and 57. It is thus obvious that through manipulation of the adjusting screws, the rollers are moved toward and from the axial center of the housing.

Mounted on the head 8 is a forwardly extending hood-like housing 58 having side walls 59 and 60 located on the respective sides of the gap 10 and a top 61. The hood-like housing is preferably formed of two sections secured together by fastening devices such as bolts 62 extending through abutting flanges 63 on the respective sections. The rear of the side walls have laterally extending flanges 64 through which cap screws 65 are extended for attachment of the housing (Fig. 5).

Rotatably mounted within bearings 67 and 68 that project outwardly from the side walls of the housing is a shaft 69 and fixed thereto within the housing is a wheel 70 having a resilient section 71 that is provided with a grooved periphery 72 for mounting the forward end of the trolley on the messenger. The shaft 69 is connected by a flexible coupling 73 with a spinning head driving mechanism 74 later described. Traction is maintained between the wheel 70 and messenger by a tensioning roller 75 that is rotatably mounted on a shaft 76 having one end pivotally connected to an arm 77 by a hinge joint 78. The opposite end of the shaft is adapted for support within the fork end 79 of an arm 80 and which is secured therein by a knurled nut 81 threadingly mounted on the end of the shaft as shown in Figs. 2 and 10. The arms 77 and 80 are located on the respective sides of the wheel 70 and have bearing portions 82 and 83 carried on the shaft 69. The arms are connected together by a cross member 84 to which is secured an eye 85 that is located in front of the wheel 70. Engaged with the eye is a hooked end 86 (Fig. 4) of a threaded rod 87 which extends upwardly through an opening 88 of the hook-like housing and carries a coil spring 89 that is sleeved thereover and which is tensioned by a knurled nut 90 threaded on the projecting end of the rod. It is thus obvious that by rotating the nut and compressing the spring, any desired tension may be effected on the messenger between the roller 75 and the wheel 70 for a purpose later described.

The cable, later described, is guided for entrance into the tubular body of the trolley by means of a spool-like roller 91 rotatably mounted on a cross shaft 92 having one end hingingly connected as at 93 with a swivel head 94 on a post 95 (Fig. 3). The post 95 is located on one side of the gap 10 of the head 8 and has a reduced threaded shank 96 threaded into a socket 97 of the head. The opposite end of the shaft is received in a slotted end 98 of a post 99 similarly anchored in the head 8 at the opposite side of the opening. The latter end of the shaft mounts a thumb nut 100 which is adapted to be threaded against the notched end of the post to prevent displacement of the roller when the roller is in position to guide the cable.

The cable spinning head includes a tubular body 101 of larger diameter than the tubular body of the trolley and is coaxially mounted therewith by means of rollers 102 and 103 that are journaled on flanges 104 and 105 located at the respective ends of the tubular body (Fig. 5), the rollers being secured to the flanges by eccentric bushings 106 mounted on cap screws 107. The faces of the rollers engage the faces of the tracks previously described. Attention is directed to the fact that there is a sufficient number of rollers located in circular series about each end of the tubular body to support the tubular body of the spinning head in coaxial relation with the tubular body of the trolley and whereby sufficient rollers are at all times engaged with the tracks to maintain coaxial alignment while other of the rollers are moving across the gap in the track member 13 at the forward end of the trolley. Since the gap at the rear end of the trolley is closed by the block 29, the rollers 103 for that end may be differentially spaced if desired. When play may occur between the faces of the rollers and the faces of the tracks, it may be taken up by adjustment of the eccentric bushings 106 on the cap screws 107.

Spaced inwardly from the ends of the tubular body of the spinning head are flanges 109 and 110 which have gaps formed therein in registry with the slot-like opening of the tubular body of the spinning head. The space between the tubular body of the spinning head and the outer circumference of the flanges 109 is closed by side walls 111 and 112 (Figs. 4 and 7). The outer peripheries of the flanges carry a cover or shield 113 that is secured thereto by fastening devices 114 to provide an enclosure for the spinning body, supporting wheels at the rear end of the trolley as well as to enclose a lock and a driven wire tension wheel later described.

The spinning head is adapted to be rotated about the axis of the tubular body of the trolley under dual drives, one of which is effected by frictional contact of the wheel 70 with the messenger when the lashing machine is in use. This is accomplished by providing the tubular body of the spinning head at a point adjacent the flange 109 with a sprocket segment 115 having ends 116 and 117 terminating on the respective sides of the gaps formed in the tubular bodies 4 and 101. Operating over the segmental sprocket is a chain 118 carried by idler sprockets 119 and 120, the idler sprockets being located so that a run 121 of the chain is at all times in engagement with a sufficient number of teeth of the sprocket to effect a drive therewith even when the gap between the ends 116 and 117 is passing the space between the sprockets 119 and 120. The chain also operates over a driving sprocket 122 as shown in Fig. 2. The chain and sprockets are mounted within a housing extension 123 that is carried on an annular flange 124 encircling the head 8 but which terminates at the sides of the head so as to avoid blocking of the passageway to the gaps formed in the tubular body of the trolley.

The annular flange 124 is of sufficient width so that it bridges the series of supporting rollers 102 at the forward end of the trolley and forms an enclosure therefore; however, the flange terminates short of the flange 109 of the opening head to accommodate the housing extension which has spaced side walls 125 and 126 (Fig. 4) and a connecting wall 127, the walls being shaped to adequately enclose the chain and sprockets and to include the space between the flanges 109

and 124 as shown in Figs. 2 and 4. The idle sprockets are mounted on the side wall 125 by fastening devices 129 and 130 as shown in Fig. 2. The driving sprocket 122 is fixed to a shaft 131 extending through a bushing 132 in the side wall 125 through a bore 133 in a bracket 134 through a bushing 135 that is carried by a bracket 136 secured to the bracket 134 by fastening devices such as cap screws 137 (see Fig. 5). The forward end of the shaft carries a pinion gear 138 that meshes with a bevel gear 139 fixed to a shaft 140 that is connected through the flexible joint 73 with the shaft 69. The gears thus described are enclosed within a gear housing 141 formed as part of the bracket 136 as shown in Fig. 5.

It is obvious that upon rotation of the foremost wheel 70 of the trolley, the shaft 69 is rotated to actuate the gears 139 and 138, the shaft 131 and the sprocket chain 118 to effect rotation of the spinning head when the lashing machine is moved in one direction.

Formed within the cover 113 at one side thereof is a recess 142 extending to the tubular body of the spinning head and of a size to accommodate a coil of lashing wire 143 on a spool 144. The spool 144 includes a disk 145 having a hub 146 journaled on a pin 147 that is fixed by a bracket 148 to the tubular body of the spinning head. The outer end of the hub 146 is reduced in diameter and exteriorly threaded to mount a plate 148 that cooperates with the plate 145 to retain the coil of wire therebetween. The hub is retained on the pin by a collar 149 sleeved on a projecting end of the pin and retained by a cotter pin 150 that extends through an opening in the collar and through a registering opening in the end of the coil supporting pin 147.

Also located on the spinning head at a side of the coil of wire, is an idle pulley 151 that is provided with a groove 152 through which the lashing wire is extended in guiding relation to a spinning wheel 153. The wheel 151 is mounted for idle movement on a cap screw 154 projecting from the spinning head. The spinning wheel 153 is adjustably supported from the tubular body of the spinning head by a bracket 155 having laterally spaced arms 156 slidable within bores of a block 158 that is secured to the tubular body by fastening devices such as cap screws 159 as shown in Fig. 4. Positioned on the bracket is a tubular spindle 161 that extends laterally therefrom through a notch-like opening 162 in the shield 113, the opening being of suitable size to accommodate the spinning wheel 153. Sleeved on the tube is a spacing washer 163 and a wheel 164 that is connected with a hub 165 of the spinning wheel. The wheel 164 is preferably formed of two parts 166 and 167, the part 167 being formed as an integral part of the hub 165 of the spinning wheel and the part 166 being clamped thereagainst by fastening devices such as screws 168. The peripheries of the wheel sections are grooved to mount a tire 169 which is adapted to frictionally engage the inner face of the head 9 so that a supplementary drive is provided for rotating the spinning head incidental to pay of the lashing wire from the spinning wheel as later described. The tubular spindle is retained in position on the bracket by a fastening device such as a bolt 173 having its shank 174 extending through a retaining washer 175 seated within a counterbore of the spinning wheel and through the tubular spindle into a threaded socket of the supporting bracket.

In order to prevent retractive movement of the

trolley and to maintain tension on the lashing wire, as later described, the shaft 69 is provided at a point within the hood-like housing with a ratchet wheel 177 adapted to be engaged by a pawl 178 best shown in Fig. 9 which is fixed to the shaft 69 by a pin 179. The pawl is mounted on a pin 180 carried by a side wall of the hood-like housing. The pawl has a tail portion 181 to be engaged by a cam 182 on a shaft lever 183 (Fig. 5). The tail of the pawl is retained in contact with the cam by a coil spring 184 having one end fixed to the tail portion of the pawl and its other end secured to a pin projecting inwardly of the hood-like housing as best shown in Fig. 5.

To facilitate placement of the machine, it is desirable to lock the spinning mechanism relative to the trolley so that the gaps of the tubular bodies are in registry. This is effected as shown in Fig. 6 by a rod 185 slideable in an opening 186 in the flange 110 and in a tubular socket 187 projecting laterally from the flange 109. Fixed on the rod is a collar 183 for seating a spring 189 that is coiled about the rod and has its opposite end seated against the flange 110 to normally effect retraction of the free end 190 from engagement with an opening 191 in the head 9. The rod is selectively moved into engagement with the opening by a lever 192 that projects through a bayonet slot 193 in the shield 113. The end of the lever carries a knob 194 by which it may be moved to shift the rod. When the arm 192 is in the portion 195 of the bayonet slot which extends in a circumferential direction, the end of the rod is retained in the opening 191 in opposition to action of the spring 189 and when the arm is in the longitudinal portion 196 of the slot, the rod is retracted by the spring 189.

To facilitate movement of the rod, the tubular socket 187 has a bayonet slot 197 corresponding to the bayonet slot just described for guiding a pin 188 carried by the rod as shown in Fig. 6.

In order to effect movement of the machine along a cable supporting strand, the forward end thereof is provided with rings 199 and 200 located on the respective side of the opening and which are adapted to be engaged by snaps 201 and 202 fixed to branches 204 and 205 of a rope 206.

Aerial cables 207 are usually temporarily supported by rings 208 from the messenger 209 and to gather up these rings progressively with the spinning, the arms 77 and 89 previously described have tubular guides 210 and 211 (Fig. 7) welded thereto for receiving the shanks 212 and 213 of fingers 214 and 215 to ride on the respective sides of the messenger and engage in the rings 208 to effect collection thereof as shown in Fig. 1.

To facilitate handling of the lashing machine, it may be provided with a handle 216 (Fig. 1) that is fixed to the flange 124 at the top thereof.

To use the machine, the aerial cable 207 is supported from the strand 209 by the rings or the equivalent 208, the strand being supported on poles (not shown). The machine is applied to the strand adjacent the end of a span. This is effected by bringing the slot-like gap of the spinning head into registry with the slot-like gaps of the tubular body of the trolley and locking the parts in this position by means of the rod 185. To shift the rod, the arm 192 is adjusted in the bayonet slot 193 so that it enters the portion 195 thereof whereupon the rod is locked against retractive movement by the spring 189. The housing section 19 is then swung to open position by

releasing the latch 31. The cable guiding spool or roller 91 is swung out of position in registry with the slot-like gap 10. This is effected by loosening the thumb nut 100 until it clears the slotted end of the post 199. Then, the spool may be swung outwardly and turned on the swivel joint so that it is out of position as shown in Fig. 7. The tension roller 75 is similarly loosened and moved from in front of the traction wheel. The machine is then ready to be applied to the cable supporting strand.

To apply the machine, it is supported so that it is passed over the strand with the strand entering the tubular body through the slot-like gaps. The traction wheels 70 and 40 then support the machine upon the cable carrying strand. The hinge section 19 is then closed and latched and the tension roller 75 is moved to a position under the cable supporting strand 209 as shown in Fig. 4. After securing the tension roller by retightening the thumb nut 81, the cable guiding spool 91 is similarly moved into position so that it is supported transversely directly below the cable 207. The pawl 178 will then be engaged with the ratchet wheel 177. The end of the spinning wire is loosened from the coil, passed into the groove of the pulley 151 and wrapped about the spinning wheel 153. The end is then anchored by a suitable clamp to the adjacent pole that carries the cable supporting strand. The rope 206 is attached to the machine by connecting the snaps 201 and 202 with the rings 199 and 200. The thumb nut 90 on the threaded rod 87 is turned to adjust tension of the roller 75 on the strand 209. The guide rollers 49, 50 and 42 may then be adjusted by means of the set screws 46, 47, 54 and 55. The locking device is then disengaged by shifting the arm 192 out of the elongated portion of the bayonet slot and into the lateral portion thereof to effect and retain disengagement of the locking rod from contact with the head 9 of the trolley. The spinning head is then free to revolve about the body of the trolley.

When draft power is applied to the rope 206 the machine is drawn along the cable supporting strand. Traction of the wheel 71 with the strand causes rotation of the shaft 69, gears 139 and 138 to rotate the shaft 131, sprocket 122 and endless chain 118. Engagement of the chain with the teeth of the ring member 115 effects rotation of the spinning head about the axis of the trolley. Since the driving chain is in contact with a greater extent of teeth than the spacing between the ends 116 and 117 of the sprocket member, rotation of the spinning head is continuous. Rotation of the spinning head carries the coil of spinning wire about the aerial cable and its supporting strand so that the lashing wire 142 is laid in a series of spirals to closely bind the aerial cable to the messenger as shown at the right of Fig. 1.

Since the lashing wire 142 has been wrapped about the spinning wheel, pay of the lashing wire rotates the spinning wheel 153 and since the spinning wheel is connected with the friction wheel 169 and the friction wheel rolls on the head 9 of the trolley, a supplementary driving force is effective whereby to rotate the spinning head. Thus, as above pointed out, I have provided a primary and supplementary drive so that should the traction wheel 70 engage wet or greasy spots in the cable and tend to slip the driving force is maintained through the friction wheel 169 with the result that a constant and substantially uniform tension is maintained on the lashing wire.

The driving ratio effected between the primary

and supplementary drives is such that when the machine is used on a medium sized cable the driving forces are substantially equal in effect; however, when the machine is used on smaller or larger cables, there is some differential between the drives and it is desirable that one of the drives be adjusted. This may be readily effected by adjusting the thumb nut 90 to vary the spring action on the roller 76 which regulates the traction of the driving wheel 70 so that any differential between the drives may be compensated for.

Attention is directed to the fact that the block 29 closes the gap in the head and track for the wheel 169, when the lower section of the wheel housing is closed, thus providing a continuous track so that the driving force of the spinning wheel is continuous.

As the machine is moved progressively along the cable carrying strand, the fingers 214 and 215 engage the temporary supporting rings and collect them thereon as shown in Fig. 1.

When the machine has reached the end of the span, the lashing strand is secured to the adjacent pole after which the slot-like gap of the spinning head is moved into registry with the slot-like gap of the tubular body of the trolley. The hinge section of the wheel housing is then opened and the tension roller 75 and cable guiding roller 91 are moved out of position so that the entire machine may be lifted from the messenger and re-applied on the opposite side of the pole. The machine is then re-adjusted on that side of the pole as above described and the operation is continued to complete lashing of the aerial cable to its supporting strand.

From the foregoing it is obvious that I have provided a cable lashing machine of simple construction wherein the spinning head is driven without the use of a gate in the driving connections and at the same time the spinning head is maintained in concentric registry with the tubular body of the trolley. It is also obvious that with the primary and supplementary drives at least one of them is effective at all times to maintain uniform tension on the lashing wire and therefore the spirals are of substantially uniform length.

What I claim and desire to secure by Letters Patent is:

1. A lashing machine of the character described including, a trolley adapted to move along a cable supporting strand, spaced annular tracks on the trolley having gaps to apply the trolley to said strand, a spinning head having a gap adapted to register with the gaps of the annular tracks, a sprocket circling the spinning head and having a gap registering with the gap of the spinning head, track engaging rollers on the spinning head, said rollers being of a number and spaced to support the spinning head coaxially of the tracks for revolution about the trolley, an endless chain, sprockets spaced apart on the trolley a distance greater than the width of the gaps for retaining a run of said chain in contact with the sprocket, and means for driving said chain to rotate the spinning head on the trolley.

2. A lashing machine of the character described including, a wheel supported trolley adapted to move along a cable supporting strand, spaced annular tracks on the trolley having gaps to apply the trolley to said strand, a spinning head having a gap adapted to register with the gaps of said tracks, track engaging means on the spinning head to support the spinning head for

revolution about the trolley, teeth arranged circumferentially on the spinning head, a flexible driving connection having contact with said teeth for a distance greater than the width of said gaps, and means connecting a wheel of the trolley with said flexible driving connection.

3. A lashing machine of the character described including, a trolley having a friction wheel adapted to move along a cable supporting strand, spaced annular tracks on the trolley having gaps to apply the trolley to said strand, a spinning head having a gap adapted to register with the gaps of said tracks, track engaging means on the spinning head to support the spinning head for revolution about the trolley, teeth arranged circumferentially on the spinning head and terminating in registry with the gaps of said tracks, a flexible driving means having contact with said teeth for a distance greater than the width of said gaps, and means connecting the friction wheel of the trolley with said flexible driving means.

4. A device of the character described including, a trolley, wheels on the trolley adapted to move along the cable supporting strand, annular tracks on the trolley having gaps to apply the trolley to said strand, a spinning head having a gap adapted to be registered with the gaps of said tracks, sprocket teeth arranged circumferentially on the head and terminating in registry with said gap of the head, an endless chain, means supporting said chain on the trolley with a run of said chain in engagement with said sprocket teeth including a driving sprocket for said chain, and a driving connection between a wheel of said trolley and the driving sprocket for effecting revolution of the spinning head on said tracks incidental to movement of the trolley along said strand when the device is in use.

5. A lashing machine of the character described including, a trolley having a friction wheel adapted to move along a cable supporting strand, spaced annular tracks on the trolley having gaps to apply the trolley to said strand, a spinning head having a gap adapted to register with the gaps of said tracks, track engaging means on the spinning head to support the spinning head for revolution about the trolley, teeth arranged circumferentially on the spinning head and terminating in registry with the gaps of said tracks, driving means having contact with said teeth for a distance greater than the width of said gaps, means connecting the friction wheel of the trolley with said driving means, and tension means cooperating with the friction wheel for gripping the cable supporting strand when the machine is in use.

6. A device of the character described including, a trolley, a friction wheel on the trolley adapted to move along the cable supporting strand, spaced annular tracks on the trolley having gaps to apply the trolley to said strand, a spinning head having a gap adapted to register with the gaps of said tracks, sprocket teeth arranged circumferentially on the head and terminating in registry with said gap of the head, an endless chain engaging the sprocket teeth, means supporting said chain on the trolley including a driver for said chain, a driving connection between said friction wheel and the driver for effecting revolution of the spinning head on said tracks incidental to movement of the trolley along said strand when the device is in use, and tension means cooperating with

11

the friction wheel for gripping the cable supporting strand when the device is in use.

7. A device of the character described including a trolley, wheels adapted for supporting the respective ends of the trolley for movement along a cable supporting strand, housings enclosing said wheels, spaced tracks on the trolley having gaps to apply the trolley to said strand, a spinning head having a gap adapted to register with the gaps of said tracks, one of said housings including a pivoted section, means on the pivoted section for closing the gap in one of said tracks, rollers on the spinning head engaging the tracks, a sprocket concentric with the spinning head adjacent the other track and having a gap registering with the gap of said track, an endless chain engaging the sprocket for a distance greater than the width of said gap in the sprocket, and a driving connection between the wheel in the other of said housings and the endless chain.

8. A device of the character described including a trolley, a traction wheel on the trolley adapted to move along the cable supporting strand, spaced tracks on the trolley having gaps to apply the trolley to said strand, a spinning head having a gap adapted to register with the gaps of said tracks, sprocket teeth arranged circumferentially on the head and terminating in registry with said gap of the head, an endless chain engaging the sprocket teeth, means supporting said chain on the trolley including a driver for said chain, a driving connection between said traction wheel and the driver for effecting revolution of the spinning head on said tracks incidental to movement of the trolley along said strand when the device is in use, and means for selectively preventing retractive movement of the trolley.

9. A device of the character described including a trolley, a traction wheel on the trolley adapted to move along the cable supporting strand, tracks on the trolley having gaps to apply the trolley to said strand, a spinning head having a gap adapted to register with the gaps of said tracks, sprocket teeth arranged circumferentially on the head and terminating in registry with said gap of the head, an endless chain engaging the sprocket teeth, sprockets supporting said chain on the trolley including a driving sprocket for said chain, a driving connection between said traction wheel and the driver for effecting revolution of the spinning head on said tracks incidental to movement of the trolley along said strand when the device is in use and a ratchet and pawl mechanism connected with the driving connection to prevent retractive movement of the traction wheel.

10. A device of the character described including a trolley having a tubular body provided with a slot-like gap to permit mounting of the trolley on an aerial cable supporting strand, heads at the ends of the tubular body and having notches registering with said slot-like gap, traction wheels on the trolley adapted to move along

12

said strand, tracks on the trolley having ends terminating at the sides of the slot, a spinning head having a slot-like gap adapted to register with the slot-like gap of said tubular body, sprocket teeth arranged circumferentially on the spinning head and terminating in registry with said slot-like gap of the head, an endless chain engaging the sprocket teeth, means supporting said chain on the trolley offset at one side of the

10 gap with a run of said chain in contact with the sprocket teeth a distance substantially greater than the width of the gap including a driver for said chain, a driving connection between one of said traction wheels and the driver for effecting revolution of the spinning head on said tracks incidental to movement of the trolley along said strand when the device is in use, a gate having means for closing the notch of one of said heads and provide a continuous circumferential face on said head, a spinning wheel, and a friction wheel having connection with the spinning wheel and rolling contact with said face for supplementing the chain drive of the spinning head.

11. A lashing machine of the character described including a trolley having a traction wheel adapted to move along the cable supporting strand, a spinning head, means supporting the spinning head for revolution about the trolley, a driving connection between the spinning head and traction wheel of the trolley, a roller carried on the trolley at a side of the strand opposite said traction wheel, and tensioning means on the trolley and connected with said roller for drawing the roller toward the traction wheel to maintain said wheel in contact with the strand.

12. A lashing machine of the character described including a trolley having a grooved wheel adapted to move along a cable supporting strand, a roller extending transversely below said wheel for supporting a cable substantially in contact with the cable supporting strand, adjustable supporting means for said roller for mounting the roller on the trolley for adjustment relative to the wheel, rollers disposed on opposite sides of said wheel and cooperating with the transverse roller in supporting the cable in alignment with said supporting strand, and yieldable means for urging said last-named rollers into rolling contact with the cable.
